PERFUME BOTTLE OR THE LIKE

Saul Polson, New York, N.Y.

Application November 27, 1957, Serial No. 48,692

Term of patent 14 years

(Cl. D58—8)

Fig. 1

Fig. 3

The characteristic features of my design for the perfume bottle disclosed reside in the collar portions encircling the neck of the bottle having the configurations shown.

I claim:

The ornamental design for a perfume bottle or the like, substantially as shown and described.
